REFORMING OF HYDROCARBONS

Robert M. Kennedy, Newtown Square, Pa., assignor to Sun Oil Company, Philadelphia, Pa., a corporation of New Jersey

No Drawing. Application November 28, 1950,
Serial No. 198,035

11 Claims. (Cl. 260—668)

1

This invention relates to a process for reforming gasoline, and more particularly to a process for reforming a gasoline having a low octane number into a gasoline having a high octane number.

Gasoline fractions derived from petroleum, such as straight run gasoline fractions, are of sufficiently low octane number to be unsuitable for use in spark-type internal combustion engines. Such fractions have heretofore been subjected to various treatments in order to increase the octane number. Such processes are generally known as reforming, since the object thereof is to reform, or convert, gasoline constituents of low octane number into high octane number constituents.

Processes heretofore employed include the dehydrogenation of naphthene constituents to aromatics using a molybdenum oxide catalyst, and isomerization to convert straight-chain to branched-chain paraffins using a Friedel-Crafts catalyst such as aluminum chloride. These processes are subject to difficulties including excessive coke formation, rapid catalyst deactivation, complicated operating manipulations, and the necessity of conducting each such process as an individual operation. It is also known that the removal of sulfur compounds, such as mercaptans, enhances the lead susceptibility of gasoline, and desulfurization has heretofore been accomplished, e. g. by extracting with caustic soda or treatment with sulfuric acid. A still further known process for reforming gasoline involves the use of a catalyst containing a minor but substantial proportion of platinum or palladium, which makes the use of a process employing this catalyst relatively expensive, and in some instances prohibitively expensive. In general, reforming processes heretofore employed involve a substantial amount of cracking whereby the higher molecular weight hydrocarbons of the charge are converted to lower molecular weight hydrocarbons, frequently forming substantial quantities of normally gaseous hydrocarbons, so that the volatility of the product is substantially lower than the volatility of the charge. In such processes it is apparent that the charge must be of a higher boiling range than the boiling range of the desired product, or, if a gasoline boiling within the desired range of the product is employed, it is necessary to blend the product with higher boiling hydrocarbons in order to increase the boiling range to the value desired. Accordingly, where reformation, i. e. an increase in octane number, of a gasoline boiling within the

2

range desired for the product is required, the cracking observed in prior processes presents a substantial disadvantage.

An object of the present invention is to provide an economical process for reforming gasoline. Another object is to provide a process for reforming gasoline wherein the several reactions which enhance the octane number and lead susceptibility of gasoline occur simultaneously. A still further object is to convert a straight run gasoline to a higher octane number gasoline without substantially changing the volatility of the gasoline. Other objects appear hereinafter.

It has now been discovered that by contacting a gasoline fraction with a catalyst consisting of a major proportion of silica and minor proportions of alumina and nickel, as hereinafter described, under certain conditions of operation, a reformation of the gasoline occurs wherein the constituents exhibiting a low octane number are converted to high octane number constituents, so that the octane number of the gasoline is greatly enhanced, and that the volatility characteristics of the product substantially coincide with those of the charge. Other advantages achieved by the present process are discussed hereinafter.

In accordance with the present invention, a gasoline fraction is contacted with a catalyst comprising silica, alumina, and nickel at an elevated temperature and under a high pressure of hydrogen. The resulting gasoline fraction exhibits an increased octane number and lead susceptibility. These advantages result from several simultaneous reactions which occur in the present process, each of which contributes to the enhanced properties of the product. The most important of these reactions is the dehydrogenation of naphthenes to form aromatics, but the isomerization of straight chain paraffins to their branched chain isomers and desulfurization substantially contribute to the enhanced properties of the product.

The catalyst of the present invention consists of a major proportion of silica and minor proportion of alumina and nickel. This catalyst and its preparation is described in U. S. Patent 2,452,190 wherein it is described as useful for the polymerization of olefins. The catalyst which may be used in the present process may contain alumina and nickel in somewhat larger quantities than described in this patent. The present catalyst contains from 60 to 99.98% of silica, from 0.01 to 25% alumina, and from 0.01 to 15% nickel, and it is important, in order to achieve the ad-

vantages of the present invention that the constituents of the catalyst be maintained within the stated ranges in order to prevent undesired reactions, such as cracking, from becoming predominant. Thus, while the presence of only relatively small amounts of alumina and nickel are required, it is essential to the present process that they be present within the concentrations stated. It is preferred to employ a catalyst consisting of from 75 to 99% silica, from 0.5 to 15% alumina, and from 0.5 to 10% nickel, since with the constituents of the catalyst within these concentrations, good results are obtained throughout the defined limits for temperature and pressure.

In order to illustrate the preparation of the present catalyst, a catalyst having an approximate composition of 98% silica gel, 1% alumina, and 1% nickel was prepared by adding one liter of an aqueous solution containing 97 grams of nickel nitrate, $\text{Ni}(\text{NO}_3)_2 \cdot 6\text{H}_2\text{O}$, and 75 grams of aluminum nitrate, $\text{Al}(\text{NO}_3)_3 \cdot 9\text{H}_2\text{O}$, to 2 kilograms of silica gel (4-8 mesh) in an evaporating dish. The mixture was evaporated to dryness, with stirring, and then ignited at a temperature of about 300° C. for about nine hours to convert the nitrates to their respective oxides. Prior to use, the catalyst mass was charged into a catalyst tube and ignited for one hour with air at 400° C. to ensure complete conversion to the oxides and to remove traces of water. It was then reduced with a slow stream of hydrogen for about nine hours at 400° C. to convert the nickel oxide to nickel. Also, for starting materials in the preparation of the catalyst composition any compound of aluminum, which upon ignition will yield alumina in activated form upon silica gel, and nickel salt, which will yield nickel oxide which can be subsequently reduced to nickel on the silica gel, can be employed. For example, freshly precipitated aluminum hydroxide can be admixed with nickel hydroxide and added to silica gel and the whole ignited and then reduced as set forth herein. Or, if desired an aluminum compound and a nickel compound can be distributed on silica gel and the entire mass ignited in air followed by reduction of the ignited mass. As stated, other methods of preparation, which will be apparent to those versed in the art, can also be employed.

As above described, the preferred catalyst of the present invention consists of silica, alumina, and nickel. However, chromia may be substituted for alumina, and cobalt may be substituted for nickel, and good results obtained therewith where the concentration of the chromia is the same as stated for alumina and the concentration for cobalt is the same as expressed for nickel. Thus, catalytic compositions consisting of silica, chromia, and nickel; silica, alumina, and cobalt; silica, alumina, and nickel; and silica, chromia, and cobalt may be employed in the present process. Also, with silica as the predominating element, both alumina and chromia may be employed either with nickel or cobalt, or with both nickel and cobalt, or both nickel and cobalt may be employed with either alumina or chromia.

The gasoline fraction which may be reformed in the present process is a petroleum gasoline fraction boiling in the range of from 60° F. to 400° F. and which contains at least 5% naphthenes. The gasoline treated may contain from 0% to 40% aromatics and from 0% to 20% olefins. A substantial advantage of the present

process accrues from the fact that olefins may be present in the charge stock without causing deleterious effects, since a cracked gasoline normally containing from about 5% to 20% olefins may be used as the charge stock without the necessity of removing the olefins. It is preferred to employ as the charge stock a straight run fraction boiling in the range of from about 150° F. to 390° F. and containing from 20% to 70% by volume of naphthenes, from about 4% to 30% by volume of aromatics, the remainder of the charge being paraffins including isoparaffins.

In many instances the charge stock will contain sulfur compounds, say up to about 1%, and in the present process the concentration thereof will be reduced, usually to negligible quantities, the actual reduction depending upon the initial concentration and the operating conditions. This desulfurization enhances the lead susceptibility of the gasoline product thereby forming an especially valuable product.

A further significant advantage of the present process is that the volatility characteristics of the product do not differ substantially from the charge stock. Thus, while a small amount of cracking occurs, as evidenced by the formation of a minor amount of normally gaseous hydrocarbons, it is not a predominant factor. Accordingly, a preferred embodiment of the present invention is the treatment of a gasoline to increase the octane number thereof without substantially changing the volatility characteristics. This emphasizes the importance of the defined upper boiling limit for the charge gasoline. If higher boiling fractions are employed, say a gas oil or kerosene fraction, considerably cracking may occur at the expense of the desired dehydrogenation of naphthenes.

The temperature to employ in the present process may be varied from 600° F. to 1,200° F. and preferably is within the range of 800° F. to 1,000° F. Pressures of from 50 to 1,500 p.s.i., and preferably from 250 to 1,000 p.s.i., give good results, such pressures being obtained and maintained by supplying an atmosphere of hydrogen. It has been found that the use of an elevated hydrogen pressure is essential to the successful operation of the present process. The optimum pressure and temperature to employ depends somewhat on the particular gasoline fraction being treated and also the hourly liquid space velocity used which may be varied from 0.1 to 10 volumes of liquid hydrocarbon oil per volume of catalyst per hour.

In the present process, at least about 30% of the naphthene content of the charge gasoline is converted to aromatic hydrocarbons, and under preferred operative conditions a much larger percent may be so converted. Hence, the product obtained has a decreased naphthene content of at least 30% and a correspondingly increased aromatic content. Also, under preferred conditions of operation, the paraffin content remains substantially unchanged, but substantial isomerization of normal to branched chain paraffins may be observed, which also serves to increase the octane number of the product.

The following examples, presented to facilitate an understanding of the present invention, illustrate preferred embodiments thereof, and are not necessarily to be considered as limiting the present invention.

Example 1

A straight run gasoline having a boiling range

of from 170° F. to 370° F. and a naphthenic content of 43 volume percent was contacted with a catalyst consisting of 98% silica, 1% alumina, and 1% nickel at a liquid hourly space velocity of 1. A hydrogen pressure of 1,000 p. s. i. and a temperature of 878° F. was maintained. Properties and compositions of the charge and product are shown below:

	Charge	Product	
		Run 1	Run 2
20% boiling point (ASTM), ° F.	216	210	207
50% boiling point (ASTM), ° F.	246	242	242
70% boiling point (ASTM), ° F.	270	268	268
90% boiling point (ASTM), ° F.	312	300	308
Refractive index n_{20}^{20}	1.4192	1.4223	1.4202
Density d_4^{20}	0.7476	0.7518	0.7487
Percent acid absorption	10.9	21.4	18.5
Composition:			
Volume percent aromatics	11	21	18
Volume percent naphthenes	43	34	30
Volume percent paraffins	46	45	52

The octane number, from an initial value of 54.5 (Research Method), was increased so that the usual addition of tetraethyl lead produces a motor fuel suitable for use in high compression internal combustion engines.

Example 2

Example 1 was repeated using the same charge gasoline, but a pressure of 500 p. s. i. and a temperature of 806° F. were employed. An increase in aromatic concentration in the product of over 36% was observed, with a corresponding decrease in the naphthene concentration, the concentration of paraffins remaining substantially unchanged.

Based on the liquid recovered, the gasoline yield was 97.2% and the yield of condensable normally gaseous hydrocarbons was 2.8%.

The above examples illustrate preferred embodiments of the present invention; when chromia is substituted for alumina, and when cobalt is substituted for nickel in the catalyst, substantially similar results are obtained.

A further important advantage of the present process is the production of relatively pure hydrogen from the dehydrogenation of naphthenes, since cracking is not an important reaction in the present process, the hydrogen produced is relatively pure, i. e. is not contaminated with substantial amounts of normally gaseous hydrocarbons, such as methane and ethane. Hence, the hydrogen produced may be recovered and employed in hydrogenation processes, such as the hydrogenation of catalytic gas oil, usually without purification. In some hydrogenation processes an especially pure hydrogen is desired, in which case if necessary the hydrogen produced by the present process may be subjected to purifying operations as known to the art.

A further embodiment of the present invention comprises the treatment of substantially pure naphthenes, or mixtures thereof, to produce by dehydrogenation the corresponding aromatic or mixture of aromatics. For example, cyclohexane, methyl cyclohexane, and the dimethyl cyclohexanes, and mixtures thereof, may be treated to produce, respectively, benzene, toluene, and the xylenes, and mixtures thereof. Where it is desired to recover the pure aromatic, it may be separated from the naphthene by methods known to the art, such as by silica gel adsorption, and the recovered naphthene may be recycled to be further converted to the corresponding aromatic.

In obtaining the data described in the above examples, and in further operation of the present process, no decrease in the activity of the catalyst was apparent after more than 10 days of continuous operation. After extended operation, however, regeneration of the catalyst may be desirable, and may be accomplished by burning off any accumulation of coke, and heating in a reducing atmosphere such as an atmosphere of hydrogen.

10 The long life of the present catalyst, and ease of regeneration when necessary, are additional advantages of the present invention over heretofore known processes.

The invention claimed is:

1. Process for reforming a gasoline fraction boiling in the range of from 60° F. to 400° F. and containing at least 5% naphthenes which comprises subjecting said fraction, at a temperature of from 600° F. to 1,200° F. and a hydrogen pressure of from 50 p. s. i. to 1,500 p. s. i., to contact with a catalyst consisting of from 60 to 99.98% silica, from 0.01 to 25% of a material selected from the group consisting of alumina and chromia, and from 0.01 to 15% of a material selected from the group consisting of nickel and cobalt.
2. Process for reforming a gasoline fraction boiling in the range of from 60° F. to 400° F. and containing from 20% to 70% naphthenes which comprises subjecting said fraction, at a temperature of from 800° F. to 1,000° F. and a hydrogen pressure of from 250 p. s. i. to 1,000 p. s. i., to contact with a catalyst consisting of from 75 to 99% silica, from 0.5 to 15% alumina, and from 0.5 to 10% nickel.
3. Process for reforming a gasoline fraction boiling in the range of from 60° F. to 400° F. and which contains at least 5% naphthenes which comprises subjecting said fraction, at a temperature of from 600° F. to 1,200° F. and a hydrogen pressure of from 50 p. s. i. to 1,500 p. s. i., to contact with a catalyst consisting of from 60 to 99.98% silica, from 0.01 to 25% alumina, and from 0.01 to 15% nickel.
4. Process for reforming a gasoline fraction boiling in the range of from 60° F. to 400° F. and which contains at least 5% naphthenes which comprises subjecting said fraction, at a temperature of from 600° F. to 1,200° F. and a hydrogen pressure of from 50 p. s. i. to 1,500 p. s. i., to contact with a catalyst consisting of from 60 to 99.98% silica, from 0.01 to 25% alumina, and from 0.01 to 15% nickel, and recovering a gasoline product of increased octane number having substantially the same volatility characteristics as said gasoline fraction.
5. Process for increasing the aromatic content of a straight run gasoline fraction boiling in the range of from about 170° F. to 370° F. and which contains from about 20% to about 70% naphthenes which comprises subjecting said fraction, at a temperature of from about 800° F. to about 1,000° F. and a hydrogen pressure of from about 250 p. s. i. to about 1,000 p. s. i., to contact with a catalyst consisting of about 98% silica, about 1% alumina, and about 1% nickel, and recovering a gasoline product having substantially the same volatility characteristics as said gasoline fraction, said gasoline product having an aromatic content at least 30% greater than said gasoline fraction.
6. Process for the dehydrogenation of a naphthene to the corresponding aromatic which comprises subjecting said naphthene, at a temperature of from 600° F. to 1,200° F. and a hydrogen

pressure of from 50 p. s. i. to 1,500 p. s. i., to contact with a catalyst consisting of from 60 to 99.98% silica, from 0.01 to 25% of a material selected from the group consisting of alumina and chromia, and from 0.01 to 15% of a material selected from the group consisting of nickel and cobalt.

7. Process for reforming a gasoline fraction boiling in the range of from 60° F. to 400° F. and which contains at least 5% naphthenes which comprises subjecting said fraction, at a temperature of from 600° F. to 1,200° F. and a hydrogen pressure of from 50 p. s. i. to 1,500 p. s. i., to contact with a catalyst consisting of from 60 to 99.98% silica, from 0.01 to 25% chromia, and from 0.01 to 15% cobalt.

8. Process for reforming a gasoline fraction boiling in the range of from 60° F. to 400° F. and which contains at least 5% naphthenes which comprises subjecting said fraction, at a temperature of from 600° F. to 1,200° F. and a hydrogen pressure of from 50 p. s. i. to 1,500 p. s. i., to contact with a catalyst consisting of from 60 to 99.98% silica, from 0.01 to 25% chromia, and from 0.01 to 15% cobalt, and recovering a gasoline product of increased octane number having substantially the same volatility characteristics as said gasoline fraction.

9. Process for increasing the aromatic content of a straight run gasoline fraction boiling in the range of from about 170° F. to 370° F. and which contains from about 20% to about 70% naphthenes which comprises subjecting said fraction, at a temperature of from about 800° F. to about 1,000° F. and a hydrogen pressure of from about 250 p. s. i. to about 1,000 p. s. i., to contact with a catalyst consisting of about 98% silica, about 1% chromia, and about 1% cobalt, and recovering a gasoline product having substantially the same volatility characteristics as said gasoline

fraction, said gasoline product having an aromatic content at least 30% greater than said gasoline fraction.

10. Process for reforming a gasoline fraction boiling in the range of from 60° F. to 400° F. and which contains at least 5% naphthenes which comprises subjecting said fraction, at a temperature of from 600° F. to 1,200° F. and a hydrogen pressure of from 50 p. s. i. to 1,500 p. s. i., to contact with a catalyst consisting of from 60 to 99.98% silica, from 0.01 to 25% chromia, and from 0.01 to 15% nickel.

11. Process for reforming a gasoline fraction boiling in the range of from 60° F. to 400° F. and which contains at least 5% naphthenes which comprises subjecting said fraction, at a temperature of from 600° F. to 1,200° F. and a hydrogen pressure of from 50 p. s. i. to 1,500 p. s. i., to contact with a catalyst consisting of from 60 to 99.98% silica, from 0.01 to 25% alumina, and from 0.01 to 15% cobalt.
